UNITED STATES PATENT OFFICE

ALBERT KOMP, OF NEW YORK, N. Y.

PULP-SHAPING MACHINE.

941,884.

Specification of Letters Patent. Patented Nov. 30, 1909.

Application filed May 20, 1908. Serial No. 433,803.

To all whom it may concern:

Be it known that I, ALBERT KOMP, a citizen of the United States, and a resident of the city of New York, borough of Brooklyn, county of Kings, and State of New York, have invented a new and Improved Pulp-Shaping Machine, of which the following is a full, clear, and exact description.

This invention is a pulp shaping machine, relating more especially to improvements in machines of the character disclosed in Letters Patent No. 868,946, granted to me October 22, 1907.

In practice I have found that considerable difficulty is experienced in detaching the shaped article from one of the dies, owing primarily to the enormous pressure under which the pulp is placed. This pressure also causes the rubber face or covering of the die to wrinkle or buckle, leaving ridges in the resulting product which it is necessary to remove ordinarily by sand papering before the article is finished. I find that I am enabled to overcome these objections by using in the place of the rubber covering of the die, a thin resilient cover, preferably of sheet metal, which is detachable with the article produced. This cover gives a smooth finish, requiring no further work for its completion.

The invention further contemplates the provision of means for locking one of the dies successively closer to the other die after each movement of the latter, whereby the pulp may be subjected to repeated and increasing pressures.

Reference is to be had to the accompanying drawings forming a part of this specification, in which similar characters of reference indicate corresponding parts in all the views.

Figure 1 is a front elevation of a pulp shaping machine partly in central vertical section, disclosing the nature of my improvements; Fig. 2 is an enlarged central sectional view of the dies; and Fig. 3 is a perspective view of the detachable die cover.

I have shown the frame of the machine to which my improvements are applied composed of a base block 5 and a head block 6, rigidly connected together at opposite sides by upright standards 7. Under the base block is journaled a shaft 8 having an eccentric 9 and a driving pulley 10 attached

thereto. Slidable centrally through the base block 5, and resting on the eccentric, is the plunger or stem 11 of a female die 12, which is shown for convenience in the shape of a basin and provided at its upper edge with an upright cylinder 13.

In the upper portion of the machine is journaled a shaft 14, driven through a gear 15 or other suitable means, and having a pinion 16, attached thereto between the standards 7, which is in mesh with the teeth 17 of a rack-bar 17. This bar is slidable through the top block 6 and carries at its lower end a male die 18, which, as shown, is made as a part of a piston head slidably fitting within the cylinder 13. The piston head is constructed with a packing ring 19, between which and the male die 18 are provided suitable recesses for frictionally engaging the ears 20, four being shown, formed integrally with a detachable die cover 21, best shown in Fig. 3, and forming one of the principal features of my improvement. This cover is made of a thin resilient material, as sheet metal, and is of such shape as to closely conform to and fit the die. On the head block 6 is pivotally supported an arm 22 having a stepped overhanging upper end 23 for engaging over the bar 17 and locking the die 18 against upward movement at varying distances from the die 12.

In the operation of the machine, the pulp is introduced into the lower die in any desired manner, and the shaft 14 set in motion in a direction to cause the die 18 to descend. As the upper die is forced firmly to the pulp in the lower die, the locking arm 22 is thrown inwardly and engages the upper end of the rack-bar with the top shoulder of the stepped portion 23. The shaft 8 is then set in motion and forces the lower die by means of the eccentric to the upper die, thus further compressing the pulp. As the eccentric makes a complete revolution, the upper die will drop down sufficiently for the locking arm to engage the rack-bar with its second shoulder, and this operation continued until the pulp has been compressed to the required point. When the upper die is withdrawn from the lower die, the article adheres to the detachable cover 21 and with it is removed. The cover is bodily removed from the finished article by striking the article a blow on the edge, when the cover flies out by re-

son of its resiliency, leaving the inside of the article with a smooth finish, requiring no further work for its completion.

By the term "bodily" as used in the specification and claims, in referring to the separation of the die cover from the article produced, I mean separating in mass, as distinguished from removal by successive portions.

10 Having thus described my invention, I claim as new and desire to secure by Letters Patent:

1. In a machine for shaping pulp articles, a die having a piston head provided with a 15 piston ring, and a thin flexible cover for the die having projecting ears adapted to be frictionally engaged between the piston head and ring.

2. In a machine for shaping pulp articles, 20 the combination of two dies between which the article is formed, means for moving one die toward the other, and means for locking the other die successively closer to the first mentioned die after each movement thereof.

25 3. In a machine for shaping pulp articles, the combination of two dies between which the article is formed, means for repeatedly moving one die toward the other, and an arm having a stepped end for locking the other die successively closer to the first mentioned 30 die after each movement thereof.

4. In a machine for shaping pulp articles, the combination of two dies between which the article is formed, means for reciprocat-

ing one of said dies, and means for locking 35 the other die closer to the first mentioned die after each reciprocation thereof.

5. In a machine for shaping pulp articles, the combination of two dies, a reciprocating member carrying one of said dies, and a device for engaging said member and locking the die carried thereby in positions successively closer to the other die after each application of pressure to the article.

6. In a machine for shaping pulp articles, 45 the combination of a male and a female die between which the article is formed, and a relatively thin resilient cover for the male die removable therefrom with the article produced and adapted to be bodily sprung from 50 said article, said die cover having a closed bottom on which the end of the male die seats.

7. In a machine for shaping pulp articles, the combination of two dies between which 55 the article is formed, and a die cover of resilient sheet material, detachably connected to one of said dies, said cover having sides inclining in a direction to facilitate its removal from the finished article.

In testimony whereof I have signed my name to this specification in the presence of two subscribing witnesses.

ALBERT KOMP.
